UNITED STATES PATENT OFFICE

LE ROY W. FAIRCHILD, OF NEW YORK, N. Y.

DESIGN FOR PENCIL-CASES.

Specification forming part of Design No. **11,432**, dated September 23, 1879; application filed August 16, 1879.
[Term of patent 7 years.]

To all whom it may concern:

Be it known that I, LE ROY W. FAIRCHILD, of the city, county, and State of New York, have produced a new and original Design for Ornamental Pencil-Cases, or cases for other small implements of the class usually denominated "watch-charms," of which the following is a full, clear, and exact description, reference being had to the accompanying photographic illustration, making a part of this specification.

A represents the complete design, including the pencil-case proper and its ornamentation. b is the ring. This ring is secured and loosely held in an eye at the closed end of the case.

d is the figure of a lizard, shown upon and forming a part of the ornamental case, at about middle distance between the two end beads e and f.

The various parts may be made of different colors when desired.

What I claim as my invention is—
A design for a pencil or other small-implementation case, consisting of the tube or shell, lizard d, ring b, eye c, and beads e and f, substantially as shown and described.

LE ROY W. FAIRCHILD.
